UNITED STATES PATENT OFFICE.

ALVIN N. EPSTEIN, OF CHICAGO, ILLINOIS.

CARTON FOR PLAYING CARDS.

1,404,945.

Specification of Letters Patent. Patented Jan. 31, 1922.

Application filed November 3, 1920. Serial No. 421,436.

To all whom it may concern:

Be it known that I, ALVIN N. EPSTEIN, a citizen of the United States, and a resident of Chicago, Cook County, and State of Illinois, have invented certain new and useful Improvements in Cartons for Playing Cards, of which the following is declared to be a full, clear, and exact description.

This invention relates to cartons for playing cards and its principal object is to provide a card containing carton, with pencil holding means and with a surface for receiving pencil writing that may be erased or washed off with the application of moisture.

The invention designs to provide a carton wherein a deck of playing cards may be conveniently carried, and which may be unfolded to expose a surface upon which the score may be kept and upon which information, concerning card games, may be printed, the carton being also provided with a pocket for the reception of a pencil, thus making provision for keeping the score of the game. The invention consists in the several novel features hereinafter set forth and claimed.

The invention is clearly illustrated in the accompanying drawing, in which:

Fig. 1 is a perspective view of a carton for playing cards, embodying a simple form of the present invention; Fig. 2 is a perspective view of carton unfolded; Fig. 3 is a perspective view of a fragment of one end of the carton, Fig. 4 is a central, longitudinal section through the carton and Fig. 5 is a detail fragmental section illustrating an additional improvement.

Referring to said drawing and first to Fig. 1, the unfolded carton or blank of which it is composed, will be seen to comprise a rectangular portion A scored along the lines a, a, e, e, to provide a rectangular portion 1 which forms the back of the carton, and scored along the lines b b, g, to form portions 2 that comprise two sides of the carton, the remainder of the rectangular part A beyond the score lines b, forming the flaps 3, 4, which are provided with interlocking means consisting of a tongue 5 on the flap 3 and a slit 6 in the flap 4. Arranged at right angles to the rectangular part A and contained between the score line e, d, is a part 7 that comprises one end of the carton, beyond which is a rectangular end flap 8. The parts 7, 8, are substantially of the same width as the part 1.

At the side of the rectangular part A, opposite the end flap 8 and extending from the score line e is a flap 15 which is scored at f, and between said score lines e, f, the flap 15 is folded upon itself and stitched or fastened together along the line h, by staples or stitches 13, to leave a tubular pocket 12 adapted for the reception of a lead pencil B. The parts 9, 10, between the score lines e, f, and the staples or seam 13 form the end of the carton opposite the end 7. The end part 11 of the flap 15 beyond the score line f is shaped as shown in Figs. 1 and 3, so as to be capable of being conveniently tucked in under the other flaps 3, 4, 8, of the completed carton. At the sides of the flap 15, beyond the score lines g, are short flaps 14 which are tucked in under the parts 9, 10.

The blank, or a part thereof, for instance the parts 1, 7, and 8, may be surfaced with a waterproof material of a nature to receive pencil writing that may be washed off or erased by the application of moisture, and this surfacing of the carton may be had by applying the waterproof solution to the entire carton or a part thereof, or a separate waterproofed sheet 16 may be secured to the body of the carton by any suitable means. The unsurfaced parts, for instance the flaps 3, 4, may receive printed matter relating to card games, to rules of games and so forth.

To inclose a deck of cards in the carton, the cards are laid on the back portion 1, the end flaps folded over the cards and the side flaps folded over and secured together by the tongue and slot connections. The cards may be removed by withdrawing the end 11 of the flap 15, thus opening one end of the carton. To make use of the carton for all of its purposes it is opened out to expose the surfaced part, upon which the score of the game may be kept with the pencil contained in the pocket.

The advantages of this article are apparent. It provides a pocket for the reception of a pencil with which score may be kept on the carton, and because of the water-proof surface thereof the score may be readily eradicated. It can be conveniently carried or stored away and when needed for use provides the several necessary accessories for playing and keeping score of card games.

Moreover, the backs or outer faces of all or any of the flaps afford spaces upon which may be placed advertising matter. The car-

ton may be used as a novelty case to contain cards and, if desired, may be sold separately from the cards. In the form illustrated in Fig. 5, the blank A may be made of leather, cloth or other strong and desirable material to which the surfacing material 16 is secured, thus providing a highly finished and more durable carton.

More or less variation of the exact details 10 of construction is possible without departing from the spirit of this invention; I desire, therefore, not to limit myself to the exact form of the construction shown and described, but intend, in the following claims, 15 to point out all of the invention disclosed herein.

I claim as new, and desire to secure by Letters Patent:

1. A carton for playing cards, comprising 20 a sheet of material comprising a front, back, sides and ends, one end of which is openable for access to the cards and has a portion thereof doubled upon and secured to itself to form a tubular pocket thereon for the reception of a pencil.

2. A carton for playing cards, comprising a sheet of material comprising a front, back, sides and ends, one end of which is openable

for access to the cards, and the material of said end being doubled on itself and the doubled part secured together along a line running across the end to form a tubular pocket adapted for the reception of a pencil.

3. A carton for playing cards, comprising a sheet of material comprising a rectangular back portion having end flaps forming the ends of the carton, and interlocking side flaps forming the sides and front of the carton, the material of one of the end flaps being doubled upon and secured to itself to form a tubular pocket extending along the length of said end of the carton and adapted for the reception of a pencil.

4. A carton for playing cards, comprising a rectangular back portion having transversely scored end flaps forming the ends and intucked overlapping front flaps for the carton, said back portion having also interlocking side flaps forming the sides and interlocked front of the carton, one of the end flaps being doubled upon itself, and the doubled portion being secured together along a line running across the length of said end to form a tubular pocket adapted for the reception of a pencil.

ALVIN N. EPSTEIN.
